UNITED STATES PATENT OFFICE.

CHARLES T. CLAYPOOLE, OF SIOUX CITY, IOWA.

ELECTRIC METER.

SPECIFICATION forming part of Letters Patent No. 694,832, dated March 4, 1902.

Application filed January 18, 1902. Serial No. 90,330. (No model.)

To all whom it may concern:

Be it known that I, CHARLES T. CLAYPOOLE, a citizen of the United States, residing at Sioux City, in the county of Woodbury and State of Iowa, have invented new and useful Improvements in Electric Meters, of which the following is a specification.

In electric meters as ordinarily constructed the shunt through which the registering mechanism is operated and controlled is connected with one of the line-wires outside the meter-casing and extends through an opening in said casing. This shunt has no effect whatever upon the flow of current through the meter to supply the translating devices; but if the same is broken the registering mechanism of the meter will cease to operate. It has been found by actual experience that dishonest consumers of current can and do disconnect or break the shunt-circuit in question by simply removing the circuit-wire from its socket in the meter-casing or by cutting it, and thereby prevent the registration by the meter of the actual current consumed. The loss to the electric companies in the different large cities from this cause is estimated at many thousands of dollars. To prevent detection, the consumer connects up the shunt prior to the visit of the inspector or meter-reader. By my invention I provide means whereby this stealing of current by the cutting out of the shunt which controls the registering mechanism is absolutely prevented. To effect this result, I locate the wire portion of the shunt-circuit wholly within the meter-casing and secure in an opening in said casing through which the shunt-wire ordinarily passes a T coupling-piece of brass, copper, or other suitable conducting material, to one arm of which the shunt-wire is attached and to the other arms of which the ends of two sections of the outer line-wire are attached.

The details of my invention will hereinafter appear, and the novel features thereof will be set forth in the claims.

In the drawing forming part of this specification, the figure thereof is a diagrammatic view illustrative of my invention.

The casing 1 of the meter may be of any suitable form of construction, but is provided with an opening 2 at one point, through which

the shunt-circuit wire controlling the meter-registering mechanism ordinarily passes. The line-wire 3 passes through the meter-casing, as is usual, and includes in series with 55 it the field-coils 4. The line-wire 5 is located wholly outside the meter-casing 1, as is usual, being connected with the line-wire 3 through the lamps or other translating devices 6. Secured within the opening 2 of the meter-casing is a T coupling-piece 7, preferably constructed of brass, although it may be made of any suitable conducting material. Said coupling-piece is solid and of sufficient thickness to prevent cutting. One arm thereof 60 extends down into the meter-casing 1 through the opening 2 and is firmly screwed or otherwise secured in place. Its lower end has connected with it the wire 8, forming part of the shunt-circuit through the meter, and the 70 other arms of said coupling-piece have attached to them the ends of two sections of the line-wire 5. By this construction it will be seen that the wire portion of the shunt-circuit through which the registering mechanism 75 is operated and controlled is wholly inclosed within the meter-casing 1 and is therefore out of reach of a dishonest consumer who would want to tamper with the same for the purpose of preventing the proper registration 80 of the current consumed by him. Furthermore, the T coupling-piece 7, which is firmly secured to the meter-casing, cannot be disconnected therefrom without opening the meter and removing the dial or registering mech- 85 anism.

Having now described my invention, what I claim as new, and desire to secure by Letters Patent, is—

1. In an electric meter, the combination 90 with the casing thereof and the line-wires, one of which extends through said casing and the other of which is located outside the same, of a shunt-circuit through which the meter-registering mechanism is operated and controlled, and a coupling-piece of conducting material extending into said casing, said coupling-piece being attached to the wire portion of said shunt-circuit and to two parts of the outer line-wire. 95

2. In an electric meter, the combination 100 with the casing thereof having an opening

therein, and the two line-wires, one of which passes through said casing and the other of which is located outside the same, of a shunt-circuit through which the registering mechanism is operated and controlled, and a ⁵ coupling-piece extending through the opening in said casing, having the inner arm thereof attached to the wire portion of said shunt-circuit, and having the other arms thereof

attached to the ends of two sections of the ¹⁰ outer of said line-wires.

In testimony whereof I have hereunto set my hand in presence of two subscribing witnesses.

CHARLES T. CLAYPOOLE.
